United States Patent Office.

JAMES W. McMILLIAN, OF GREENVILLE, ALABAMA.

Letters Patent No. 91,035, dated June 8, 1869.

IMPROVEMENT IN VELOCIPED.

The Schedule referred to in these Letters Patent and making part of the same.

To all whom it may concern:

Be it known that I, JAMES W. McMILLIAN, of Greenville, in the county of Butler, and State of Alabama, have invented a new and improved Velocipede; and I do hereby declare that the following is a full, clear, and exact description thereof, which will enable others skilled in the art to make and use the same, reference being had to the accompanying drawing, forming part of this specification, in which—

Figure 1 represents a vertical longitudinal section of my improved velocipede, the plane of section being indicated by the line $x-x$, fig. 2.

Figure 2 is a plan or top view of the same.

Figure 3 is a detail vertical transverse section of a modification of the same.

Figure 4 is a detail longitudinal section of another modification of the same.

Similar letters of reference indicate corresponding parts.

This invention relates to a new three or four-wheeled velocipede, which is so constructed that motion can be imparted to both axles at once, either by the hands or feet of the operator, or by both hands and feet combined.

The invention consists in the general combination, with ratchet-wheels mounted on both axles, of connecting-levers, all arranged in such a manner that the aforementioned results can without difficulty be realized.

A, in the drawing, represents the frame of my improved velocipede, supported on the front axle B and rear axle C, both these axles being hung in their bearings, so that they can revolve in the same.

The wheels D and E are respectively mounted on these axles.

On each axle are also firmly mounted two ratchet-wheels F F.

Each of these ratchet-wheels is enclosed in a cylindrical box, G, which is hung loose on the axle, and which has one arm a projecting forward from it. The two ratchet-wheels on the front axle are respectively in line with those on the rear axle, so that the boxes G on the front axle may be connected with those of the rear axle respectively.

This connection is made in each case by means of a horizontal lever, H, which has its ends, by means of vertical rods b b, respectively connected with the ends of the arms a of the front and back boxes, as shown in fig. 1.

In each arm a is fitted a sliding click, c, which is, by means of a spring, d, forced against the edge of the ratchet-wheel,

When the lever H is pushed down, these clicks will act on the ratchet-wheels, and will draw them around, so as to turn the axles and propel the vehicle.

When, however, the lever H is moved up, the clicks will slide on the ratchet-wheels without acting on them, and will come into position again for another downward stroke.

From each lever H projects a rod, e, up through the frame, said rod carrying a foot-plate, f, at its upper end.

A spring, g, has the tendency to elevate said foot-plate, and with it the lever H.

The rider throws his weight alternately from one foot-plate to the other, and will thereby propel the vehicle, the springs G throwing up the foot-plates whenever the weight is removed from them.

From the front boxes G project backward other arms a', similar to the arms a, they being connected with handles I I, as shown.

Each arm a' contains a click, c', which is, by means of a spring, d', thrown against the edge of the ratchet-wheel, so that by each upward motion of the handle I, motion will be imparted to the axles. Thus the feet alone, or only the hands, or both hands and feet, may be used for propelling the vehicle.

The driver may stand upon the foot-plates, or may operate them when seated on a seat, J.

The steering-device of this apparatus may be of suitable construction.

Instead of the clicks c c' and springs d d', above described, the clicks may be formed on spring-shanks, as in fig. 3, or they may be made in form of loose tubes, fitted around the axle, to catch with their toothed ends against the toothed ends of a shoulder, h, mounted on the axle, as in fig. 4.

In this latter case the sliding clutches i i are, by springs j j, held against the toothed shoulder, and have projecting arms a a' to operate in the manner above described.

Having thus described my invention, What I claim as new, and desire to secure by Letters Patent, is—

The combination, with the two axles of a velocipede, carrying the ratchet-wheels F, of the herein-described spring-clicks, arms a a', rods b b, levers H, and handles I, all arranged and operating substantially as herein shown and described.

JAMES W. McMILLIAN.
